OIL GAS APPARATUS

Application filed June 29, 1925, Serial No. 40,389, and in France July 12, 1924.

The present invention relates to oil gas apparatus; and its object, stated briefly, is to provide an apparatus which is structurally analogous in some respects to that shown and described in our prior Patent No. 1,630,048, granted May 24, 1927, but which, in the main, is an improvement on or development of the earlier form to render it applicable for gas making. The particular improvements involved will be explained in the course of the description which follows.

In the accompanying drawings:

Figures 1 and 2 are diagrammatic vertical sections, taken at right angles to each other, of one form of oil gas apparatus embodying our invention;

Fig. 3 is a vertical sectional view of a second form;

Figs. 4, 5 and 6 are vertical sections of other modified forms of apparatus.

The apparatus illustrated in said drawings can be used equally well with heavy hydrocarbons and oils and with mixtures of different heavy and light hydrocarbons.

The oil gas making apparatus shown in Figs. 1 and 2 comprises a casing A through which pass tubes B, both the casing and the tubes being made of a suitable catalytic metal or alloy, such as copper, nickel, or a copper-nickel alloy. In the interior of the tubes B, hot gases, such as engine exhaust gases, circulate and the entire casing is disposed within an outer casing C from which it is spaced to provide an intermediate passage A'; such passage having an inlet A² and an outlet A³ for said gases.

The inner casing A is provided with two branches; one of which branches (indicated at D) may have a suitable carbureter E communicating with it, while the other branch F terminates at the induction pipe of an internal combustion engine. The carbureter E and branch pipe D serve jointly to supply to the casing A, under the action of suction, a mixture of primary air and finely atomized fuel such as oil which, on contact with the superheated walls of the hot gas circulation tubes B arranged like a baffle, is gasified, the presence of the catalytic metals or alloys being intended to render the said gasification

more thorough and to produce it as soon as the temperature reaches, for instance, 330° C.

The casing A may be provided with one or more chambers G inserted in the path of the mixture of air and atomized fuel; and these chambers may be filled with absorbent materials, such as pumice, charcoal, etc., either alone or mixed with copper or other metal filings, or they may contain metal filings alone, or other catalyzing substances. Copper or other metal gauze may be used for holding these substances which in certain cases may be agglomerated so that they will not be carried away by the suction of the engine when the gasifier is used therewith. The purpose of the chambers is to absorb the excess liquid fuel and then vaporize it, the chambers being exposed, like all the other parts of the inner casing A, to the action of the heating gases; and another purpose of said chambers is to supply water during gas making, the water being converted into steam which mixes with the hydrocarbon vapors and air, one of the chambers being provided for the purpose with a water inlet pipe H.

Fig. 3 shows a modified construction in which the hot gases circulate outside a nest of tubes B' terminating at opposite ends in conduits D' and F'; the conduit D' constituting the inlet for the mixture of air and oil, and the conduit F' constituting the oil gas outlet. The nest of tubes may, of course, be filled with a suitable absorbent metallic substance in order to absorb the excess liquid fuel, and also to increase the decomposition and gasification of the oil.

In Figs. 4 and 5, the inner casing consists of a single chamber G' exposed within and without to the action of the hot exhaust gases. This chamber G', like the above-mentioned chambers G, is filled with absorbent substances mixed with metal filings, or with metal filings alone, which substances may be agglomerated or held by metal gauze. The catalyzing action may be exerted either by the walls of the chamber or by the substance or substances filling the said chamber, and the chamber may be supplied at I with liquid fuel alone or in combination

with water, alcohol, or their mixtures, which may be admitted at J. The water or aqueous liquid supplied at J serves to hydrogenate the mixture of hydrocarbon vapors and air.

Whenever suction is applied at F², it is necessary to combine the gases from the liquid fuel with air in order to obtain a combustible mixture. To that end, the apparatus may be provided with an adjustable pipe K which may be supplied with compressed air or with atmospheric air in the former case in order to increase the rate of suction and the output of oil gas. The part 10 of the apparatus containing the absorbent or catalyzing substances may be detachable and accessible for inspection.

In the modified construction shown in Fig. 6, the inner casing A is divided into several parts or compartments, the functions of which are as follows:—

The first or bottom compartment a contains the tubes B in which circulate the hot exhaust gases, said tubes being surrounded 25 by metallic or non-metallic absorbent material, as already described. The liquid fuel from the tank L fills this compartment without passing beyond the top thereof. Under the action of the heating gases, the fuel is 30 vaporized and partly decomposed and passes into the second compartment b, in the form of more or less moist vapors.

Before entering the latter compartment, however, these vapors pass through or 35 across suitable screening devices or bodies M (baffle plates, metal gauze or the like) arranged in their path which will catch and remove foreign matters that they may contain, such as asphalt, tar or other impurities. The said compartment a may be used 40 for the absorption of the water, alcohol or mixtures thereof coming from tank N, and the level of which, as stated above in connection with the fuel, does not rise above 45 the top of the compartment. The action of the aqueous liquid is the same as before.

The second or intermediate compartment b is designed to superheat the vapors of the fuel alone or the mixture of vapors of fuel 50 and steam. Owing to the heat of the gases circulating in the outer casing or jacket C, these vapors may be maintained in a sufficiently hot state to prevent them from condensing.

The third or top compartment c is utilized 55 to gasify the vapors of the hydrocarbons or of the different mixtures coming from the compartment a which may be termed the absorption and distillation chamber. These vapors are first screened and separated from foreign matters by the devices M previously mentioned, such purification taking place merely under the action of suction; but in 65 certain cases, a pump or an injector may

obviously be used in order to increase the speed of suction.

In the passage or oil gas outlet F³, which may connect the apparatus to the intake of an engine, not shown, is mounted an adjustable nozzle K, the object of which is to supply additional air to the fuel vapors.

The same apparatus may be used for enriching lean gases coming for instance from gas producers. The first compartment a of the gas generating chamber hereinbefore described (Fig. 6) may also be used for the distillation of coal and the production of producer gas, and the upper compartments b and c may be used for enriching these 75 gases. The economy of this apparatus is due to the utilization of hot exhaust gases for the production of the gases, and to the enrichment of the lean gases by the catalysis of the heavy hydrocarbons. The apparatus also contributes to the purification 80 of the gases.

We claim as our invention:—

1. Oil gas apparatus, comprising inner and outer casings spaced from each other to provide circulation passage for hot gases at opposite sides of the inner casing, one side of such passage having an inlet for the hot gases, and the other side having an outlet therefor; a nest of tubes of catalytic metal extending through said inner casing and opening at their ends into said passage to conduct said fluids from the inlet side thereof to the outlet side; an oil gas delivery pipe leading from the upper part of the inner casing through the outer casing to the outside; means for supplying a mixture of finely pulverized hydrocarbon liquid and air to the lower part of said inner casing to be divided into fine streams by the tubes and decomposed catalytically to form oil gas by direct contact with the heated surfaces thereof during their passage to the delivery pipe; and means for supplying an aqueous liquid to the said lower part 100 of the inner casing to facilitate the catalytic action.

2. Oil gas apparatus, comprising inner and outer casings, the former containing loose catalytic material, spaced from each other to provide an intermediate circulation passage for hot gases at opposite sides of the inner casing, one side of such passage having an inlet for the hot gases, and the other side having an outlet therefor; a nest 115 of tubes of catalytic material of high thermal conductivity extending through said inner casing and opening at their ends into said passage to conduct said gases from the inlet side thereof to the outlet side; an oil gas delivery pipe leading from the upper part of the inner casing through the outer casing to the outside; means for supplying a mixture of finely pulverized hydrocarbon liquid and air to the lower part of said inner 120 125 130 inner casing to facilitate the catalytic action.

casing to be divided into fine streams by the tubes and decomposed catalytically to form oil gas by direct contact with the heated surfaces of the tubes and loose material during their passage to the delivery pipe; and means for supplying an aqueous liquid to the interior of the inner casing to facilitate the catalytic action of the tubes and loose material.

5 10 In testimony whereof we affix our signatures.

DMITRY BALACHOWSKY.
PHILIPPE CAIRE.
